COMPRESSOR OR PUMP

Harold M. Gingrich, Oakland, Calif.

Application February 18, 1942, Serial No. 431,347

5 Claims. (Cl. 103—143)

This invention is primarily designed for compressing or pumping gases though it may be used for moving or pumping any type of fluid. As is well known, there are many types of compressors which are not adaptable to the pumping of liquids, while this invention will pump liquids as readily as it will pump gases. So far as is known, none of the compressors which are now available can be statically and dynamically balanced, while this new invention can be both, statically and dynamically balanced. All known compressors discharge by impulse thus inducing a reaction which sets up vibration, while this compressor compresses only against an existent pressure with substantially uniform discharge so that no vibration is developed.

The objects and advantages of the invention are as follows:

First; to provide a fluid mover which can be used as a pump or compressor for gases, or a pump for pumping liquids.

Second; to provide a device as outlined which is capable of being dynamically and statically balanced due to the absence of any eccentrically-operated members and therefore being capable of vibrationless operation.

Third; to provide a device as outlined in which fluids, contrary to standard practice for devices of this type, are delivered under substantially uniform flow conditions and thus eliminating vibration, whether the device is used for pumping liquids or for compressing gases.

Fourth; to provide a compressor which is constructed with an absolute minimum of parts and which are simply and economically formed and machined, resulting in a compressor of the lowest possible manufacturing cost.

In describing the invention reference will be made to the accompanying drawing, in which:

Fig. 1 is a cross-sectional elevation through the invention and is taken on a line 1—1 of Fig. 2.

Fig. 2 is a section taken on line 2—2 of Fig. 1.

Fig. 3 diagrammatically illustrates the operation of the invention.

The invention consists of a housing 10 having a cover 11 which is suitably secured to the housing as by screws 12. A rotor 13 rotatably fits within the housing 10 and is formed integral with or mounted on a straight cylindrical shaft 14 which is supported in bearings 15 and 16 respectively in the hub 17 which is formed axially on the cover 11, and hub 18 which is formed axially on the housing 10.

Fixedly secured to the cover 11 is a pinion 19 ~~as~~ 3, vane 22 when in the position 22a has the end

which is illustrated as being formed integral with the bushing 15. The rotor has a groove 20 which is formed in one end face concentric to the axis of the shaft 14, the bottom of the groove being indicated at 20'. A pin 21 is fixed in the end wall of the housing 10 and extends inwardly to slidably cooperate with the bottom 20' of the groove 20 and slidably cooperates with the side walls of the groove. This pin functions as the abutment for the compressor or pump.

Rotatably mounted in the rotor parallel to the axis of the shaft 14 is a plurality of angularly spaced vanes 22, 23, which are cylindrical in form and have each a slot 25 equal in depth to that of the groove 20 and of equal width and adapted to slidably pass over the abutment 21. A gear 26 is formed integral with or mounted on the other end of each vane and these gears mesh with the pinion 19. With large installations the number of vanes could be increased over the two illustrated, and obviously, by changing the gear ratio, and providing a plurality of intakes and discharges, the compressor or pump can be made to intake and discharge fluid at the rate of several cycles per revolution of the rotor. As illustrated there are but two vanes with one intake and one discharge per revolution of the rotor. With the arrangement illustrated the gear ratio is 1:2 so that for 180° of movement of the rotor the vanes will rotate through only 90° on their own axes. For two intakes and two discharges with four or more vanes the gear ratio would be 1:1 and an abutment 21 would be provided for each intake and discharge cycle per revolution.

The operation of the invention is as follows: The abutment 21 blocks the flow of fluid within the groove 20. Rotation of the rotor causes the vanes to rotate on their own axes one-half revolution for each revolution of the rotor. The two vanes therefore have their slots at right angles to each other so that when one is aligned to pass the abutment, the other is at right angles to the groove in the rotor to block the groove.

Obviously, the parts could readily be reversed; that is, the groove could be formed in either the housing end wall or in the cover and the vanes would then be mounted in the same element in which the groove was formed, while the abutment would be mounted in the rotor, thus the abutment would function as the fluid driving member.

Referring to the diagrammatic illustration Fig.

of its slot spanning the abutment, and due to the fact that the angular movement of the vane is exactly equal to half of the angular movement of the rotor, the slot will constantly line up with the abutment while the vane passes the abutment. When vane 22 is in the position 22b, vane 23 is in the position 23a with the slot 25 at right angles to the groove 20. As vane 22 moves to the position 22c, vane 23 moves to the position 23b forcing the fluid in the groove 20 toward the abutment while the space 27 between these two vanes is filled with fluid. With further movement of the rotor, vane 22 passes the intake 28 and closes the groove as indicated at position 22d while vane 23 moves to the position 23c in which position the groove seal is broken with all of the work of moving the fluid transferred back to vane 22, the fluid being discharged through the outlet 29. Thus each vane in turn moves the fluid from the position 22d to position 23c, further discharge being then taken up by the following vane. The exact angular position where this transfer takes place depends upon the diameter of the vane and the relative width of the groove, but under the most practical conditions is located approximately at the 90° and 270° locations of the vanes measured from the abutment.

Thus it will be noted that no compression or constriction actually takes place within the compressor due to any internal restrictions and that pressure is only built up as the external resistance is increased. Since there is no build-up in pressure within the unit, the device will pump water or other liquids as readily as it will pump or compress air and no fluid-lock can result. It will also be noted that the rotor can be both, statically and dynamically balanced, and due to the constant substantially non-pulsating delivery of fluid, that the device will be substantially free of vibration.

Methods of oiling, of valving the discharged fluid, and other details are well known in the art and are therefore not illustrated or described.

I claim:

1. A fluid mover, in combination, two members including a housing and a rotor rotatably fitting within said housing; a shaft axially mounted in said housing and axially secured to said rotor; a groove concentrically formed in one face of one of said members; a plurality of cylindrical vanes rotatably mounted in said rotor and having each a diameter greater than the width of said groove and axially located centrally of the width of said groove and having each a slot formed therein equal in width and depth to that of said groove and alignable therewith; an abutment fixed in the other member and extending to the bottom of said groove and slidably fitting in said groove; an intake passage on one side of said abutment and a discharge passage on the other side and communicating with said groove; and means cooperating between said other member and said vanes for rotating said vanes through 360 degrees on their own axes coincident with rotation of said rotor on its axis.

2. A fluid mover comprising; a cylindrical housing having an abutment projecting inwardly from one end thereof; a rotor rotatably fitting within said housing and having a concentric groove slidably fitting said abutment; a shaft for said rotor; a plurality of cylindrical vanes mounted in said rotor parallel to the axis thereof and having each a groove of the same cross-sectional dimensions as said concentric groove formed in one end and alignable with said concentric groove to pass

5 said abutment and rotatably mounted to block said concentric groove during a portion of one revolution of said rotor and to pass said abutment during another portion of the revolution; means cooperating between said housing and said vanes for rotating said vanes on their own axes when said rotor is rotated; and an intake passage and a discharge passage communicating with said groove respectively on opposite sides of said abutment; said means cooperating between said housing and said vanes comprising a pinion fixed to said housing and a gear fixed on the other end of each vane and meshing with said pinion.

3. A fluid mover comprising; a housing having a cylindrical bore; a rotor rotatably fitting within said bore; a shaft axially mounted in said housing and rotatably supporting said rotor; an abutment projecting inwardly from one end face of said housing; a concentric groove formed in said rotor and slidably receiving said abutment with the abutment extending to the bottom of said concentric groove for sliding cooperation therewith; an intake passage on one side of said abutment and a discharge passage on the other side and communicating with said groove; cylindrical vanes mounted in said rotor and having their axes parallel to the axis of said rotor and located centrally of the width of said concentric groove and having a diameter greater than the width of said concentric groove and having each a groove formed inwardly from one end with dimensions equal to the cross-sectional dimensions of said concentric groove; a gear on the other end of each vane and a pinion axially mounted on the housing and meshing with said gears for rotating said vanes on their own axes when said rotor is rotated.

4. A housing having a cylindrical bore and a cover, and a cylindrical abutment projecting inwardly from one end wall within the bore and parallel to the axis of the bore; a rotor rotatably fitting within said cylindrical bore and having a concentric groove formed in one end thereof slidably fitting said abutment; a shaft integral with said rotor and rotatably mounted axially in said housing; cylindrical vanes rotatably mounted in said rotor parallel to the axis thereof and having each a diameter greater than the width of said concentric groove and with their axes located approximately centrally of said concentric groove and having each a diametric slot formed inwardly from one end with cross-sectional dimensions equal to that of the said concentric groove and having each a gear mounted on the other end; a pinion axially secured to said cover and meshing with said gears; an intake passage located on one side of said abutment and a discharge passage located on the other side, and communicating with said groove.

5. A compressor comprising; a housing having a cylindrical bore, a fixed head and a removable head, an axial hub on said fixed head and having an axial bore, and an axial hub on said removable head and having an axial bore, and a cylindrical abutment projecting inwardly from said fixed head; a rotor rotatably fitting in said cylindrical bore and having a shaft rotatably fitting in said bores in said hubs; a groove formed concentric to the axis in one end face of said rotor and slidably fitting said abutment; an intake passage formed in said fixed head on one side of said abutment and communicating with said groove; a discharge passage formed in said fixed head on the other side of said abutment and communicating with said groove; a plurality of equi-

angularly spaced cylindrical vanes rotatable in bores formed in said rotor and having their axes located centrally of the width of said groove and having each a slot formed in one end alignable with said groove with said slot and said groove having identical cross-sectional dimensions; a gear fixed on the other end of each vane, and a

pinion mounted axially on said removable head; whereby, when said rotor is rotated, said vanes are rotated on their own axes to align the slot with said groove when the vane reaches said abutment and move the vanes crosswise of the groove after passing the abutment.

HAROLD M. GINGRICH.
